(57) CLAIM

The ornamental design of metal studded underwear waistband, as shown and described.

DESCRIPTION

FIG. 1 is a left side elevational view of a surface pattern applied to a pair of underwear showing my new design, the right side being a mirror image;

FIG. 2 is a front elevational view thereof, the rear being a mirror image;

FIG. 3 is a second embodiment showing the left side view thereof, the right side being a mirror image;

FIG. 4 is a front elevational view thereof, the rear being a mirror image;

FIG. 5 is a third embodiment showing the left side view thereof, the right side being a mirror image; and,

FIG. 6 is a front elevational view thereof, the rear being a mirror image.

The underwear and human form are shown for illustrative purposes only and form no part of the claimed design.
